MULTIPLE ASH TRAY

Susan A. Thompson, Casper, Wyo.

Application July 3, 1956, Serial No. 42,135

Term of patent 3½ years

(Cl. D85—2)

Fig. 1.

Fig. 3.

Fig. 2.

Fig. 4.

Fig. 5.

Fig. 6.

I claim:

The ornamental design for a multiple ash tray, as shown.
